UNITED STATES PATENT OFFICE

148,419

DESIGN FOR A SERVING TRAY

Charles J. Jacobsen, Washington, D. C.

Application January 31, 1947, Serial No. 136,569

Term of patent 14 years

(Cl. D44—10)

To all whom it may concern:

Be it known that I, Charles J. Jacobsen, a citizen of the United States and a resident of Washington, District of Columbia, have invented a new, original, and ornamental Design for Serving Tray, of which the following is a specification, reference being had to the accompanying drawing, forming part thereof, in which

Figure 1 is a plan view of the serving tray showing my new design.

Figure 2 is a vertical sectional view thereof on line 2—2 of Figure 1, and

Figure 3 is a longitudinal sectional view thereof on line 3—3 of Figure 1.

I claim:

The ornamental design for a serving tray, as shown and described.

CHARLES J. JACOBSEN.
